(57) **CLAIM**

The ornamental design for a lancing device, substantially as shown and described.

DESCRIPTION

FIG. 1 is perspective view of a lancing device according to a first embodiment of the design.

FIG. 2 is first side view of the lancing device design of FIG. 1.

FIG. 3 is a second side view of the lancing device design of FIG. 1.

FIG. 4 is a front view of the lancing device design of FIG. 1.

FIG. 5 is a rear view of the lancing device design of FIG. 1.

FIG. 6 is a top view of the lancing device design of FIG. 1; and,

FIG. 7 is a bottom view of the lancing device design of FIG. 1.

Portions shown in broken lines are for illustrative purposes only and form no part of the claimed design.
